SURFACE TREATING APPARATUS

Filed Sept. 1, 1949

UNITED STATES PATENT OFFICE

2,637,948

SURFACE TREATING APPARATUS

Lewis H. Bishop and John S. Finn, Burlingame, Calif., assignors, by mesne assignments, to William H. Mead, Oakland, Calif.

Application September 1, 1949, Serial No. 113,524

13 Claims. (Cl. 51—14)

1

This invention relates to a surface treating apparatus and more particularly to apparatus which may be used to abrade a path, such as a margin along the edges of sheet metal preparatory to welding, soldering or otherwise securing said edges together.

One important use of the invention is the cleaning of metal sheets preparatory to welding, soldering, or otherwise fastening together the edges of cans, drums, tubing and other cylindrical objects, but the invention is not limited to such use. It may be used wherever edges of sheet materials are to be cleaned, whether on one side or on both sides, or wherever a margin or other path is to be thoroughly cleaned from rust, grease, paint and other foreign matter.

Edge cleaning, whether in preparation for weld seaming or for any other purpose, has heretofore been a difficult, time-consuming operation. The cleaning must be perfect, for foreign matter will repel solder, and spoil welds, and thereby cause imperfect seams so that the container or pipe will leak. Moreover it often becomes necessary to clean the margin of a metal sheet having a lithographic print or other painted matter on its surface, and care must be taken to clean the margin perfectly without injuring the paint.

Another important problem in quantity manufacture of seam welded tubular articles has been how to obtain an edge-cleaning apparatus which can perform the desired operation at a sufficiently rapid rate of speed to keep up with the other machinery in a production line. Moreover the rapidity must be achieved without any sacrifice in accuracy. Also it is desirable to achieve automatic operation in a production line.

The present invention solves these problems and enables rapid automatic cleaning of edge margins along one or both sides of sheet material, as well as other paths. It does this by providing a novel apparatus operating according to the method of the William H. Mead Patent No. 2,455,514, issued December 7, 1948. The general method and apparatus described in the aforesaid patent include means to impel abrasive against a surface in an air blast and to withdraw spent abrasive by a suction current which is more intense than the impelling air blast. The operating head may include an air-permeable, abrasive-confining maze, so that a stream of air is drawn into the head by the suction current and impinges with the air blast stream inside the maze to carry away the spent abrasive.

In the present invention the operating head is

2

known as an edge blasting box. It includes a housing having a slit therethrough; a pair of blast nozzles positioned on opposite sides of the sheet, so as to project abrasive against the edge of the sheet, which is passed between the nozzles; and a suction opening where the spent abrasive is withdrawn. An air-permeable abrasive-confining maze fills the slit, keeping the abrasive inside the box and permitting the entry of an air stream which subsequently passes into the suction current. The maze is made in two sections, and the sheet material whose edge is being blasted is fed in and out of the box between these two sections. The housing may also be provided with guide means to position the sheets being treated. Moreover, the box may be combined with automatic propelling means for continuously treating the sheet material.

Other objects and advantages of the invention will appear from the following description of a preferred embodiment. The description is illustrative and is not intended as a narrow limitation of the invention. The scope of the invention will be apparent from the claims.

25 In the drawings:

Fig. 1 is a view in elevation and partly in section of an apparatus embodying the principles of the invention. Two edge-blasting boxes are shown mounted at each side of a conveyor table, and the sheet material whose edges are to be cleaned is moved along the table. Each box is hinged so that it may be swung open, and its open position and the then position of its associated conduits are shown in dotted lines.

30 Fig. 2 is a view in elevation and in section of one of the edge-blasting boxes taken along the line 2—2 of Fig. 1.

35 Fig. 3 is a view in section along the line 3—3 of Fig. 2; and

40 Fig. 4 is a side elevation of a portion of a box of Fig. 1 with the maze-like member removed therefrom.

45 Fig. 1 shows a frame 10 which supports a conveyor table 11. A pair of continuous chains 12 and 13 may be moved across the table 11 by a motor (not shown) so as to propel sheet material 15 along the table 11. A guide rail 14 may be secured to the edge of the table 11 to keep the sheets 15 in line. In their course across the table 11 the edges 16 and 17 of the sheets 15 pass through two edge-blasting boxes 20, where a margin 18 along each of the two side edges 16 and 17 is cleaned preparatory to welding.

50 55 Each box 20 includes two housing sections; an

upper housing section 21 and lower housing section 22. The lower housing section 22 may be secured rigidly to a pair of brackets 23, which in turn may be rigidly secured to the frame 10 by wing nuts 24. A similar pair of brackets 25 may be secured to the upper housing section 21. The brackets 25 are preferably mounted pivotally at 26 to the lower brackets 23, either directly or through adjustable arms 27.

Thus the upper section 21 may be pivoted back around the pivot member 26 so as to open up the box 20, in order to permit access to the inside of the box 20. This position is shown in dotted lines on Fig. 1. The pivot bolt 26 may be tightened to hold the sections 21 and 22 together rigidly when the box 20 is closed.

The upper section 21 is substantially a cylinder, open at its lower end 30 and closed at its upper end 31 except for a central opening 32 (see Fig. 2). More than half of its lower end 30 is relieved at 33 (see Fig. 4). This relieved level 33 cooperates with a corresponding relieved portion 43 in the lower housing 22 to provide a groove 34 through which the plate 15 can pass and also where the air permeable abrasive impeding means may be held. The upper edge 33 of the groove 34, terminates in a shoulder 35 which may provide the upper half of a guide means for the sheets 15 instead of the rail 14, if desired. The groove 34 preferably extends beyond the center of the box 20, so that the blast nozzles may be centrally located.

The lower section 22 is open at its upper end or mouth 40, and closed at its lower end 41 except for a central opening 42. Its upper end 40 is cut-back at 43 (see Fig. 4) to provide the lower edge 43 for the groove 34. The shoulder 45 may cooperate with the shoulder 35 to complete a guide means for the edge of the plate 15, in place of the bar 14. The non-relieved portions 36 and 46 of the two housings 21 and 22 fit snugly together when the box 20 is assembled.

The lower housing 22 also includes a side opening 47 through its walls. Preferably the side opening 47 is angular and is downwardly inclined, and connects with an integral fitting 48. A suction hose 49 attached to the fitting 48 withdraws the spent abrasive and waste material, in conformance with the aforementioned Patent 2,455,514.

Blast nozzles 50, 60 are provided to fit respectively in the central openings 32 and 42 of the housing sections 21 and 22. The nozzles 50, 60 are preferably positioned directly opposite each other, although they may be staggered where the abraded paths are to be out-of-line instead of in-line. The nozzles 50, 60 connect respectively with blast conduits 51, 61. Each nozzle 50, 60 is preferably made from or lined with a very hard material such as silicon carbide. From a relatively wide entrance passageway 52, 62, it tapers down to a long narrow outlet orifice 53, 63 terminating in a mouth 54, 64. The purpose of making the orifice 53, 63 long and narrow is to gain a high velocity of impingement of the abrasive and also to keep the abrasive material from spreading too much when it issues from the nozzle 50, 60. When striking the metal sheet 15, the total spread of the abrasive will be the width of the margin 18 being cleaned. For most purposes this will be about $\frac{1}{4}$ inch. The spread may be varied by moving the nozzles 50, 60 up or down in the openings 32, 42. This may be done by unscrewing the set screws 54a and 64a. When the set screws are loose, the nozzles may be moved both vertically

and rotationally to adjust for wear and to change the width of the treated area.

For protection of the metal parts, the nozzles 50, 60 are encased in protecting rubber members 55, 65, and the interior portions of the housing sections 21, 22 adjacent the mouths 30, 40 are equipped with rubber linings 56, 66. The rubber members 55, 65, and the linings 56, 66 protect the metal parts from the abrasive which strikes the work piece and flies off. If desired, the other exposed portions of the nozzles and housing can be similarly lined. On the abutting portions 36, 46 of the mouths 30, 40 the rubber linings 56, 66 abut where the box 20 is closed, as in the solid line position in Fig. 1, so as to form a seal on this part of the box and prevent any spilling of abrasive between the abutting housing sections 21, 22.

The groove 34 is enclosed by an air-permeable maze, which extends around the box 20, and is split to provide entry for the plate 15. In the form here shown the maze comprises a pair of annular bristle brushes 70, 80 held in adjustable collars 71, 81. The collars 71, 81 include overhanging flanges 72, 82 (see Fig. 2) which narrow the maze openings and thereby cause a more intense air current to impinge with the blast current and sweep away the abrasive. Set screws 73, 83 provide for both vertical and horizontal adjustment of the brushes 70, 80. By this arrangement, the brushes may be rotated so that the brushes wear evenly, and may be raised and lowered to compensate for the gradual shortening of the bristles as they wear out and also for the thickness of the sheet 15 being cleaned. Rubber rings 74, 84 may be provided to seal off any passage of air between the collars 71, 81 and the housing sections 21 and 22.

In operation, equipment such as that shown in Patent No. 2,455,514 may be employed to impel an abrasive-filled air stream into the conduits 51 and 61. One machine of the type there shown will be sufficient for two boxes 20; the four conduits 51 and 61 may all lead off one main blast conduit 85. Similarly the same apparatus may provide suction in the conduit 86 to which the two suction conduits 49 for both boxes 20 are joined.

In operation, the sheets 15 are propelled along by the conveyor members 12 and 13, and are guided by the bars 14. They pass into the boxes 20 beneath the nozzles 50, 60, and the margin 18 is abraded. The abrasive is impelled simultaneously through the nozzles 50, 60 in each box 20 and strikes the margin 18 on both sides of the sheet 15. The air current entering through the brushes 70, 80 impinges with the blast current and sweeps the spent abrasive into the suction conduits 49.

No abrasive is spilled because the box 20 is closed, and the suction current carries away all the spent abrasive. With automatic conveying machinery the sheets may be cleaned at a rate of 45 feet per minute, or more, continuously, each sheet being simultaneously cleaned on both sides of both side edges. The high speed of movement is a factor in preventing distortion of the sheets 15. The path 18 may be blasted on only one side, by proper connection of the blast conduits, and again the high speed will prevent distortion.

It will be understood that the invention is not limited to edge-treating apparatus. It may be used to clean any path across a sheet of material. In order to do this, the opening 34 will then extend all the way across the box, and there will be

a suction opening 47 on both the upper and lower sections 21 and 22.

Furthermore, the apparatus may be used on curved edges. It may be used to clean an annular path in a disc or other sheet, by combining it with a different type of conveying machinery, which will turn the sheet instead of impelling it forward.

Also the boxes 20, here shown positioned vertically, for horizontal cleaning, may be positioned vertically or at an angle, if desired.

We claim:

1. An apparatus for abrading a marginal surface area adjacent an edge of metal sheets while confining the abrasive and preventing it from flying about, comprising a hollow imperforate cylindrical housing having a slit extending somewhat more than half way across it, the shoulder at the end of said slit acting as a guide for the sheets passing therethrough; a pair of blast nozzles held in the center of said housing, one on each side of said slit; a pair of maze-like air-permeable abrasive-impeding means secured to said housing and filling said slit so that the sheets can be passed into said housing between said pair of means; and an opening through said housing adapted to be connected to a low-pressure suction line.

2. The apparatus of claim 1 in which the housing comprises two cylindrical housing members pivotally held adjacent one another so that they can be swung apart, the open mating faces of said housing members having mating relieved portions covering more than half of their circumference to form said slit and said shoulder when they fit together.

3. The apparatus of claim 1 in which said maze-like means are a pair of brushes mounted in opposition to each other and terminating adjacent each other, each brush being mounted in a collar which is adjustable on said housing.

4. An apparatus for continuously treating a marginal surface area adjacent an edge of metal sheets while confining the treating material and preventing it from flying about, comprising a main frame; conveying means mounted on said frame; a hollow housing mounted to one side of said frame and having a transverse slit therethrough; a pair of blast nozzles in said housing generally facing each other on opposite sides of said slit; means to impel treating material through said nozzles; a maze-like impeding means filling the slit, said maze-like means being split so that sheet material propelled along said frame by said conveying means may be passed into said housing therethrough; an opening through the walls of said housing; and suction means connected to said opening for removing spent treating material therefrom.

5. An apparatus for continuously treating a surface strip of sheet material while confining the treating material and preventing it from flying about, comprising a main frame; conveying means mounted on said frame; a hollow housing mounted to one side of said frame and having a generally transverse opening therethrough; a pair of jet means in said housing generally facing each other on opposite sides of said opening; means for impelling treating material through said nozzles; an air-permeable maze-like means surrounding said opening and having a transverse passage-way therethrough for receiving sheet material into said housing; guide means for determining the path of said sheet material; a conduit passing into said housing; and suction means con-

nected to said conduit for removing spent treating material therefrom.

5 6. An apparatus for continuously cleaning two opposite marginal edges of sheet metal, comprising a main frame; conveying means mounted on said frame; a pair of hollow housings, one mounted to each side of said frame, each housing having a transverse slit therethrough; a pair of blast nozzles in each said housing with their mouths facing in opposite sides of said slit; means to impel treating material through said nozzles; a pair of maze-like impeding means surrounding each slit so that sheet material propelled along said frame by said conveying means may be passed into said housing between them; an opening through said housing; and suction means connected to said opening for removing spent treating material therefrom.

10 7. An apparatus for treating a marginal surface area adjacent an edge of a metal sheet while confining the treating material and preventing it from flying about, comprising a hollow imperforate housing comprising two hollow members pivotally secured together, the mouths 15 of said members being relieved to provide a slit on one side thereof at their juncture and a shoulder adjacent said slit where the relieved portion of the mouth ends so that said shoulders may act as a guide for the sheets passing through the said slit, which forms a transverse opening extending part of the way through the side walls of said housing; a pair of blast nozzles held in said housing, one on each side of said transverse opening with their openings generally opposite each other; an air-permeable maze-like abrasive-deflecting means filling said transverse opening, said means having a transverse line of separation 20 so that sheet material can be passed into said housing through said line of separation; and a conduit passing through the walls of said housing and adapted to be connected to a low-pressure suction line.

25 8. An apparatus for treating a marginal surface area adjacent an edge of a metal sheet while confining the treating material and preventing it from flying about, comprising a hollow imperforate housing having a transverse opening extending part of the way through its side walls; an interior protective layer of rubber lining the inner surface of said housing, the surface of said layer being exposed, said layer extending a substantial distance above and below said transverse opening so as to cover substantially the entire surface of the portion of said housing against which treating material ordinarily strikes after its deflection by the metal sheet being treated; a pair of blast nozzles held in said housing, one on each side of said transverse opening with their openings generally opposite each other; an air-permeable maze-like abrasive-deflecting means filling said transverse opening, said means having a transverse line of separation so that sheet material can be passed into said housing through said line of separation; and a conduit passing through the walls of said housing and adapted to be connected to a low pressure suction line.

30 9. An apparatus for treating a marginal surface area adjacent an edge of a metal sheet while confining the treating material and preventing it from flying about, comprising a hollow imperforate housing having a transverse opening extending part of the way through its side walls; a pair of blast nozzles held in said housing, one on each side of said transverse opening with their openings generally opposite each other,

said nozzles being adjustable rotationally and vertically with respect to said housing so as to enable even wear of the nozzles, to correct for wear and to bring them nearer to each other or farther apart and thereby change the width of the impelled treating material where it impinges on the sheet; an air-pervious maze-like abrasive-deflecting means filling said transverse opening, said means having a transverse line of separation so that sheet material can be passed into said housing through said line of separation; and a conduit passing through the walls of said housing and adapted to be connected to a low-pressure suction line.

10. An apparatus for treating a marginal surface area adjacent an edge of a metal sheet while confining the treating material and preventing it from flying about, comprising a hollow imperforate housing having a transverse opening extending part of the way through its side walls; a pair of blast nozzles held in said housing, one on each side of said transverse opening with their openings generally opposite each other; a pair of air-pervious maze-like abrasive-deflecting brushes filling said transverse opening, said brushes having a transverse line of separation terminating in substantially planar contact with each other so that sheet material can be passed into said housing through said line of separation; and a conduit passing through the walls of said housing and adapted to be connected to a low-pressure suction line.

11. The apparatus of claim 10 in which each of said brushes is mounted in a collar and in which said collars are adjustably secured with respect to said housing, whereby the brushes may be rotated, brought closer together, and moved farther apart to compensate for wear and for the thickness of the sheets being treated.

12. The apparatus of claim 11 in which the 40 collars each include an overhanging rim outside

said brush so as to restrict and intensify the entering air current.

13. An apparatus for continuously treating a marginal surface area adjacent an edge of a metal sheet while confining the treating material and preventing it from flying about, comprising a hollow housing having a slit opening through a portion of its walls, so that a metal sheet can be slid along in a straight line with one edge and its adjacent area passing through said slit into and out of said housing; a pair of opposed peripheral air-pervious brushes secured to said housing and enclosing said slit to permit the transverse passage therethrough of said metal sheet and the maze-like passage of air inwardly therethrough while preventing the outward passage therethrough of the treating material; a pair of treating-material-impelling means in said housing facing each other on opposite sides of said slit opening; and suction means for removing spent material from said housing during operation of the device in a current of air.
